PRIMUS EMERSON, OF CARONDELET, MISSOURI.

Letters Patent No. 82,395, dated September 22, 1868.

IMPROVEMENT IN PADDLE-WHEELS.

The Schedule referred to in these Letters Patent and making part of the same.

TO ALL WHOM IT MAY CONCERN:

Be it known that I, PRIMUS EMERSON, of Carondelet, in the county of St. Louis, and State of Missouri, have made certain new and useful Improvements in Paddle-Wheels; and I do hereby declare that the following is a full and clear description thereof, reference being had to the accompanying drawings, and to the letters of reference marked thereon.

The object of this invention is to construct the paddle-wheel in such a manner that the paddles will remain vertical at all times, thus securing the entire efficiency of the propulsive power of the wheel, without feathering the paddles, as many inventions for this purpose do.

In this invention, each one of the paddles is pivoted, by means of a couple of journals on its ends, to the outer ends of the wheel-arms, or to an annular rim connecting the ends of the said arms. Each of these pivoting-journals has a crank, on the outer side of the wheel, which cranks are attached to an annular cam-rim, held constantly in an eccentric position by the side of the wheel, by means of fixed sheaves, the whole operating so as to hold the paddles in a constantly vertical position.

To enable those skilled in the art to make and use my improved paddle, I will proceed to describe its construction and operation.

Figure 1 of the drawings is a side elevation of the improved wheel.

Figure 2 is a transverse central sectional elevation of the same.

The wheel-arms A are attached to the bosses B, which are secured to the shaft C, in the usual manner. The arms are likewise connected together, and strengthened by means of the annular rims D D'. The paddles E are attached to the outer ends of the wheel-arms, or to the outer rims D', (connecting them,) by means of short journals e, and on the outer ends of these journals, and outside of the rims D', are cranks e', the wrists of which are engaged by the cam-rims F. The paddles are allowed to rotate freely on their journals e. The cam-rims F are circular plates, placed parallel with the sides of the wheel, and eccentrically to its shaft. The rollers G, fixed in position at the sides of the wheel, hold the cam F up in a certain fixed (relative) position, and thereby compel the cranks e' to remain continually in a vertical position, and, with them, the paddles E also remain vertical.

It will readily be seen that the paddles enter and leave the water in vertical positions, and move forward in vertical positions while in the water, thus securing all the benefits of feathering-paddles, and, at the same time, securing a wheel of sufficient strength to withstand the severe usage to which it is applied.

The journals e, by means of which the paddles are attached to the rim of the wheel, are placed at the bottom edge of the paddle; hence the paddles are not liable to be broken or bent out of place, by coming in contact with logs or other hard substances.

If iron paddles be used, the journals e may be formed on the ends of a continuous shaft, placed across the wheel, from side to side, behind the paddle, and this shaft will strengthen the paddle in its central part; but, if continuous shafts be used for this purpose, they should be reduced somewhat in their central parts, so as to diminish the resistance in entering and leaving the water.

Having described my invention, what I claim, is—

The paddles E, when hinged to the outer rim of the wheel by means of journals e, placed at their bottom edges, substantially as described and set forth.
